UNITED STATES PATENT OFFICE

WALTER ANDERSEN, OF ST. LOUIS, MISSOURI

FLASK SUPPORTER

Application filed June 6, 1927. Serial No. 196,723.

This invention relates to flask supporters designed and adapted to support flasks for the administration of saline and other solutions. The device is specially useful as an accessory for surgical uses, though it may be applied to other purposes.

An object of the invention is to provide a device for supporting a flask for the application of saline and other solutions and indicating accurately the amount of such solutions administered and otherwise facilitating the administration of the solutions.

Other objects will appear from the following description, reference being made to the drawing, in which,

Fig. 1 is an inverted end view of the flask for the administration of saline and other solutions and having my invention applied thereto.

Fig. 2 is a side elevation of a flask with the present device applied thereto.

Fig. 3 is a side elevation looking at right angles to Fig. 2.

Fig. 4 is an enlarged cross sectional view approximately on the line 4—4 of Fig. 3.

The flask 1 is of familiar globular type provided with an elongated neck 2 and which type of flask is used extensively in connection with surgical operations, etc. The construction and uses of the flask are quite familiar to physicians, surgeons and their aids and attendants and further description is unnecessary.

The present invention comprises means for supporting the flask inverted so as to obtain accurate administration of the contents. As shown, a disc 3 constitutes a base and is shaped to provide a number of beads 4 for the better support of the flask in upright position on the disc 3.

A pair of arms 5 extend across and engage the bottom of the flask and are attached to diametrically opposite sides of the disc 3 and these arms are curved and shaped in conformity with the contour of the body of the flask 1 and have their ends extended to fit against diametrically opposite sides of the neck 2 of the flask, but terminate short of the open end of the neck 2. These arms 5 have a band or ring 6 attached to their extremities

arranged to clasp around the neck 2 of the flask. The ends 7 of the band or ring 6 are extended outwardly and are capable of being spread apart to permit application of the device to the flask in placing the band or ring around the neck of the flask, or to permit removal of the device from the flask. To one of the extended ends 7 one end of a wire 8 carrying beads 9 is secured. The other end 7 of the ring or band 6 is provided with a notch 10 adapted to receive the wire 8 so that the beads 9 will hold the ring or band 6 clasped on the neck 2 of the flask. This fastener device 8—9 may be removed from the notch 10 to permit the band or ring 6 to be opened and removed from the flask neck but, in all cases, will remain suspended from the end 7 to which the end of the wire 8 is attached.

A resilient wire 11 has one end attached to the band or ring 6 and the other end bent laterally to provide a hook 12 arranged to extend against the outer end of the stopper 13 of the flask neck. The wire 10 with the hook 12 formed thereon is a resilient device which functions to hold the stopper securely in the neck of the flask and to hold the disc 3 securely against the bottom of the flask and to prevent the device from moving in either longitudinal direction.

A bail 14 has its ends pivoted to ears 15 formed in connection with the arms 5 slightly above the plate 3, so that the flask may be set upon its end without obstruction by the ears 15 while the bail 14 may be turned to either side of the flask. When the flask is in use, the bail 14 may be used to suspend the flask in inverted position.

One or both of the arms 5 may be provided with a graduated scale 16 to indicate accurately the amount of contents of the flask and the amount removed in each administration.

This invention has been used successfully and with a high degree of satisfaction as a supporter for flasks used in the administration of saline and other solutions. The invention may well be applied to other uses and the construction and arrangement of the parts thereof may be varied without depar-

ture from the nature and principle of the invention.

Accordingly, I do not restrict myself in these or any other unessential particulars, but what I claim and desire to secure by Letters Patent is:—

1. The combination with a flask having a neck, and a stopper in the neck, of a base for supporting the flask upright with the neck extending upwardly, a pair of arms located on diametrically opposite sides of the flask and neck and secured to said base, a clasp attached to said arms and engaging the neck of the flask, and a resilient element having one end connected with said clasp and extending to engagement with the end of the stopper and preventing outward movement of said stopper.
2. The combination with a flask having a neck, and a stopper in the neck, of a support for the flask comprising a pair of arms on diametrically opposite sides of the flask and neck and engaging the bottom of the flask, a ring clasp attached to said arms and engaging the neck of the flask and having its ends detached from each other and capable of being spread apart to permit application of the ring on the neck or removal of the ring from the neck of the flask, a resilient element attached to said clasp and extending to engagement with the end of the stopper and constituting an abutment preventing outward movement of the stopper, and a bail pivoted to said arms near the bottom of the flask and being movable laterally to position to permit said flask to stand upright with the neck extending upwardly.
3. A device for administration of solutions comprising a flask having a neck, and a stopper in the neck, in combination with a frame secured to the flask, a graduated scale on the frame indicating the amount of contents of the flask, a bail pivoted to the frame for supporting the flask inverted and being movable to position to permit the flask to stand upright with the neck of the flask extending upwardly, and a resilient element having one end rigid with said frame and the other end extending to engagement with said stopper to prevent outward movement of said stopper when said flask is inverted.
